SHOE AND METHOD OF MAKING THE SAME

Fred Belyea, Braintree, Mass., assignor to United
Shoe Machinery Corporation, Paterson, N. J.,
a corporation of New Jersey

Application November 9, 1934, Serial No. 752,330

9 Claims. (Cl. 12—142)

This invention relates to shoes and to methods of making them. The shoe disclosed herein as an illustrative embodiment of the invention is a shoe of the type in which a portion of material like that from which the sole is made extends up the side of the shoe to a predetermined line on the upper, thus giving the shoe the appearance of having a very thick sole and protecting the shoe upper from being knocked or marred when worn in playing rough games such, for example, as the Cuban game of Jai Alai.

Objects of this invention are to provide a satisfactory shoe of this type and a method by the practice of which it is practical to manufacture the shoe with existing machinery.

My novel shoe is characterized by having about its periphery a folded strip of material the fold of which is located along a line at a predetermined, substantially uniform distance above the sole and the outer layer of which covers the edge face of the sole and has its edge flush with the bottom of the sole. The inner layer of the strip extends with the upper over the bottom of the insole and may be included with the upper and the welt in the weltling operation, the inseam then securing the welt, the margin of the inner layer of the folded strip, and the upper to the lip of the insole. Preferably the strip, the welt and the outsole are of raw rubber, for example the kind of raw rubber known to the trade as crepe rubber.

Considered in its method aspect, the invention comprises lasting an upper, preferably of leather, over an insole in any usual or preferred manner, roughing the sides of the upper along a band extending preferably entirely around the shoe, the upper edge of said band being located at a predetermined distance above the inner face of the insole, applying cement, such as rubber cement, to the roughened area, attaching to the upper by means of the cement the mid portion of a strip of material such as crepe, one marginal portion of the strip lying against the overlasted upper, applying an outsole, preferably of crepe, to the shoe bottom, and securing the other marginal portion of said strip to itself and to the edge face of the outsole. If desired, a lipped insole may be used and a welt, preferably of crepe, applied to the margin of the strip which overlies the overlasted upper and sewed to the lip of the insole along with the strip and upper. The inseam will then be trimmed, the shoe filled, an outsole applied to the shoe bottom in contact with the welt, and

the other or outer marginal portion of the strip secured to itself and to the edge faces of the welt and the outsole.

These and other features and aspects of the invention will appear more fully from the following detailed description when read in connection with the accompanying drawing.

In the drawing,

Fig. 1 represents a lasted shoe having a band of upper material next to the shoe bottom 10 roughened;

Fig. 2 is a sectional detail showing the attachment of the intermediate portion of a strip of material to the roughened portion of the upper;

Fig. 3 is a sectional detail showing the inner marginal portion of the strip united with the upper and a welt to the lip of the insole;

Fig. 4 is a sectional detail showing the inseam trimmed, the shoe filled and the outsole applied;

Fig. 5 is a sectional detail showing the outer marginal portion of the strip secured to itself and to the edge faces of the welt and outsole;

Fig. 6 is a perspective view of the completed shoe; and

Fig. 7 is a sectional detail illustrating a modified form of the invention.

One illustrated method of practising the present invention consists in assembling an upper 10, preferably of leather and including a lining 12, with a lipped insole 14 upon a last 16, lasting the upper over the feather of the insole and against the lip 18 thereof, and securing the upper temporarily in lasted position, for example, by staples 20 driven through the upper and the lip of the insole. A portion of the side of the upper adjacent to the insole is then roughened as illustrated at 22, the roughened portion forming a band, preferably of substantially uniform width, extending up the side of the shoe to a line located at a predetermined distance above the inner face of the insole, the upper edge of said line being indicated at 24 in Fig. 2. If desired, the roughening may be extended to include a portion or all of the overlasted portion 45 of the upper.

Cement such as rubber cement is then applied to the roughened band 22 and, if desired, to the overlasted portion of the upper, and the intermediate portion of a wide strip 26, preferably of crepe rubber, is applied to the roughened and cemented portion, as illustrated in Fig. 2. The inner portion of the crepe rubber strip is then sewed with a crepe rubber welt 28 and the upper 10 to the lip 18 by a seam 30, as il-

lustrated in Fig. 3. The inseam is then trimmed substantially flush with the welt, a usual filling material 32 introduced to fill the space bounded by the inseam, and a crepe rubber outsole 34 attached to the shoe, as illustrated in Fig. 4.

This attachment is preferably effected by moistening the welt and the marginal portion of the outsole with a solvent for rubber, such as gasoline, and pressing the shoe and sole together. If necessary, a trimming operation may be performed to insure that the edge faces of the welt and sole are flush with each other, and then solvent is applied to the edge faces of the sole and welt and to the outer surface of the strip 26 while it is in the position shown in Fig. 4. The free marginal portion of the strip 26 is then brought into the position shown in Fig. 5, a portion of this part of the strip being laid against the portion which was cemented against the side of the shoe and the remainder thereof engaging the edge faces of the welt and outsole. Pressure is applied to the strip to insure that it will adhere firmly to the edge faces of the outsole and welt and to itself. The portion of the strip 26 which projects beyond the outer face of the outsole is then trimmed off flush with that outer face, the shoe bottom then presenting the appearance illustrated in Fig. 6.

It is to be understood that when two surfaces of crepe rubber are moistened with a solvent such as gasoline and pressed firmly together they unite very strongly; in fact, the union is a cohesion rather than an adhesion since no cementing material is introduced and the solvent soon evaporates. Therefore, the crepe parts thus treated may properly be said to be welded together or homogeneously united.

If desired, a simpler construction, illustrated in Fig. 7, may be employed. Here, the wide strip of crepe is omitted and a wide welt 28' is sewed at its inner edge with the upper to the lip of the insole. The outsole 34 is then solutioned to the portion of the welt overlying the lasted upper, and the outer portion of the wide welt is turned down over the edge face of the outsole and solutioned thereto, any excess material of the welt 28' being trimmed off flush with the bottom of the outsole.

Having thus described my invention, what I claim as new and desire to secure by Letters Patent of the United States is:

1. A shoe having a lipped insole, an upper, an outsole, and a strip of material secured with the upper to the insole and secured to the side of the upper up to a line on the upper at a predetermined distance above the plane of the inner face of the insole, said strip being folded upon itself along said line and united to itself and to the edge face of the outsole.

60 2. A shoe having a lipped insole, an upper, an outsole, and a strip of material sewed to the lip of the insole, secured to the upper below a line on the upper at a predetermined distance above the plane of the inner face of the insole, folded upon itself along said line, and united to itself and to the edge face of the outsole.

65 3. A shoe having a lipped insole, an upper, a welt, an outsole, and a strip of material sewed with the upper and welt to the lip of the insole, said strip being secured to the upper along a line on the upper at a predetermined distance above the plane of the inner face of the insole, folded

upon itself along said line, and united to itself and to the edge faces of the welt and outsole.

4. A shoe comprising an upper, a lipped insole, a welt, an outsole, and a folded strip of material the fold of which is located against the upper and along a line at a substantially uniform distance from the shoe bottom, the inner layer of said strip being secured to the insole lip between the welt and upper and the outer layer of said strip extending across the edge faces of the 10 welt and the outsole and being trimmed flush with the bottom face of the outsole.

5. A shoe having a lipped insole, an upper, a crepe rubber outsole, and a strip of crepe rubber sewed to the lip of the insole, cemented to the 15 upper below a line on the upper at a predetermined distance above the plane of the inner face of the insole, folded upon itself along said line, and united to itself and to the edge face of the crepe rubber outsole.

20 6. That improvement in methods of making shoes which comprises lasting an upper over an insole upon a last, roughing the upper at the side of the shoe from a line at a predetermined distance above the plane of the insole and including a portion of the overlasted upper, cementing the roughened portion, securing the mid portion of a strip of material to the upper by said cement, securing one marginal portion of the strip to the insole, applying an outsole, and 30 securing the other marginal portion of the strip to the edge face of the outsole.

25 7. That improvement in methods of making shoes which comprises lasting an upper over a lipped insole upon a last and securing it to the 35 lip of the insole, roughing the upper at the side of the shoe from a line at a predetermined distance above the plane of the insole and including a portion of the overlasted upper, cementing the roughened portion, securing the mid portion of a strip of material to the upper by said 40 cement, securing one marginal portion of the strip to the lip of the insole, applying an outsole, and securing the other marginal portion of the strip to the edge face of the outsole.

45 8. That improvement in methods of making shoes which comprises lasting an upper over a lipped insole upon a last, roughing the upper at the side of the shoe below a line located at a predetermined, substantially uniform distance 50 above the insole, securing an intermediate portion of a strip of material to the upper by said cement, securing one marginal portion of the strip with a welt to the insole by stitches, trimming the upper, filling the shoe, applying an outsole, and securing the other marginal portion of the strip to the edge face of the outsole.

55 9. That improvement in methods of making shoes which comprises lasting an upper over a lipped insole upon a last, roughing the upper 60 at the side of the shoe below a line located at a predetermined, substantially uniform distance above the insole, securing an intermediate portion of a strip of crepe rubber to the upper by said cement, securing one marginal portion 65 of the crepe rubber strip with a crepe rubber welt to the insole by stitches, trimming the upper, filling the shoe, applying a crepe rubber outsole, and securing the other marginal portion of the strip to the edge faces of the welt and 70 outsole.
